UNITED STATES PATENT OFFICE.

JOHN F. OHMER, OF DAYTON, OHIO.

PRINTING MECHANISM FOR TICKET ISSUING AND AUDITING MACHINES.

1,056,765.

Specification of Letters Patent.

Patented Mar. 18, 1913.

Original application filed July 24, 1908, Serial No. 445,165. Divided and this application filed April 25, 1910. Serial No. 557,324.

To all whom it may concern:

Be it known that I, JOHN F. OHMER, a citizen of the United States, residing at Dayton, in the county of Montgomery and State of Ohio, have invented certain new and useful Improvements in Printing Mechanism for Ticket Issuing and Auditing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in printing mechanism and is especially adapted for use in connection with ticket-issuing and auditing machines, such as is shown in my former Patent No. 974,511 of Nov. 1, 1910, from which the present application is divided.

The object of the invention is to provide a printing mechanism for ticket issuing and auditing machines that will impart different feeding movements to the ticket and record strips, thereby economizing in the amount of paper used.

In setting forth the present improvements I have shown them associated with a ticket-issuing and auditing machine as disclosed in the several drawings.

Referring to said drawings, Figure 1 represents a front elevation of the left side of the machine with the casing and some of the parts removed. Fig. 1^a is a view of the right side of the machine, the same being a continuation of Fig. 1. Fig. 2 is a section on the line *d d* of Fig. 1. Fig. 3 is a section on the line *e e* of Fig. 1^a. Fig. 4 is a side elevation of the cash counter mechanism, some parts being broken away. Fig. 5 is a top plan view of the cash counter. Fig. 6 is a side elevation of the visible counter showing means for actuating the same and the means for actuating the printing counters. Fig. 7 is a view of the cash counter setting cam. Fig. 8 is a view of the ticket as issued by a machine provided with a consecutive printing counter. Fig. 9 is a view of the printed record for the ticket shown in Fig. 8. Fig. 10 is a view of tickets issued from a machine not having a consecutive printing counter but in which the tickets are numbered before being placed in

the machine. Fig. 11 is a view of the printed record of the tickets shown in Fig. 10. Fig. 12 is a side elevation of the outside of the machine. Fig. 13 is a front elevation of the outside of the machine. Fig. 14 is a diagrammatic view of the cash-counter ratchet and cam devices. Fig. 15 is a modification of the setting means for the month and day printing devices. Figs. 16 and 17 are detail views of the station and price-printing devices.

Throughout the specification and drawings, similar reference characters indicate corresponding parts.

Frame-work.—Referring to Figs. 1 and 1^a, 2, 3 and 4 designate plates between which the mechanisms of the machine, exclusive of the printing mechanism are mounted. These frames are attached to the rear plate 5 and bottom plate 6. The printing mechanism is mounted in the plates 7, 8 and 9 at the bottom of the machine, which mechanism will be hereinafter more fully described.

Manually set printing wheels.—Extending through the plates 1, 2, 3 and 4 is a shaft 10 upon which the various type wheels are mounted. These type wheels are in duplicate, the series for printing the ticket being on the left side of the machine as the operator faces it, and the series for printing the record being on the right side as the operator faces the machine. Near the ends of the shaft 10 are mounted duplicate month wheels 11 and 12, which are provided with gears 13 and 14. These type wheels rotate in unison through gears 15 and 16 on shaft 17 which mesh with the gears 13 and 14. The shaft 17 is journaled in the plates 1, 2, 3 and 4. Lying on the right side of the month wheels 11 and 12, are duplicate day wheels 18 and 19 which are provided with gears 20 and 21. These wheels rotate in unison through means of gears 22 and 23 on shaft 24 similar to the month wheels. Lying next to the month and date wheels on both sides of the machine, are type wheels 25 and 26, which rotate in unison as they are both attached to the shaft 10. The wheel 26 on the right side of the machine is provided with a gear 27. These type wheels 25 and 26 print on the face of the ticket and the record, the class of ticket that is being issued, such as a clergy, half fare, first class, second class, etc., and a star as will be seen

105
110

from sheet 7. The type wheels 11, 12, 18 and 19, and 25 and 26 are set from the outside of the machine by means of drums 28, 29 and 30 which are mounted on telescopic shafts 31, 32 and 33 respectively. These shafts are provided with gears 34 and 35 and 36 which mesh with the gears 21, 14 and 27 of the type wheels. The type wheels are held in printing alinement by springs 31^a engaging the gears 34, 35 and 36. The above-described mechanism is old and is found in my former patents, particularly Patent No. 874,424 of December 24, 1907.

Consecutive printing counters.—Lying on the outside of the plates 2 and 3 and pivoted on the shaft 10, are left and right consecutive number printing counters A and B. These counters have type wheels 37 and one tooth transfer wheels 38 of well known type. The transfer wheels 38 are mounted on the shaft 39. The type wheels 37 are held in printing alinement by springs 38^a. These counters A and B are actuated concurrently by means of the shaft 39, the unit actuating gears 41 of both counters being rigidly secured to said shaft. The means for actuating the printing counters A and B will be described in connection with the visible counters.

Destination type wheel setting mechanism.—Mounted between the plates 2 and 3 and pivoted on the shaft 10, are duplicate type wheels 42 and 43, the peripheries of which contain printed characters representing the destination and the price of the ticket. The type wheels 42 and 43 may be each formed of four separate wheels 42, 42^a, 42^b and 42^c, on the periphery of one of which the stations are engraved, and upon the peripheries of the other three, blank surface spaces are provided, one for each station, and numerals to print the prices are engraved on the surface spaces of the three wheels, the numeral on one wheel to print the units, the numeral on one wheel to print the tens, and the numeral on one wheel to print the hundreds (or dollars). Holes are drilled on the flat side of each wheel including the station wheel. The four wheels are fastened together with a pin on screw 42^d which compels them to revolve together on the shaft 10. It is thus seen that in the event the prices are subsequently changed to a lesser or greater value, for example, "Lima 4.80" to "Lima 4.85," it will only be necessary to replace the first or unit wheel with a new wheel to print "5" in place of "0" and thereby the tens and dollar wheels and the station wheels are preserved. When this alteration is made, the corresponding pin 68, on one of the cams 69, 70 or 71, is also changed so that the adding value of the pin 68 will correspond with the fare. It is thus seen that the price wheels or

the engraved prices on the price wheels may be omitted from the combined type wheels 42 which print on the tickets, in which case the prices will be printed only on the record. The wheels 42 and 43 rotate concurrently by means of the drum 44 and are set from the shaft 45 by means of the transfer gears 46, 47 and 48 shown in Fig. 2. Mounted on the outside of the machine on the shaft 45 is a drum 49; this drum indicates on its outer surface the different stations and the fare. 50^a designates a pointer under which the drum 49 rotates and is instrumental in selecting the desired station when a ticket is to be issued. The type wheels 42 and 43 are held in a printing position by means of a roller 51^a on the spring controlled bell crank lever 52^a. The roller 51^a engages serrations on the cash counter setting cam 70.

Total cash counter.—As before stated, the type station wheels are provided, in addition to the type denoting the station, with type denoting the cost of the ticket, and the object of the cash counter is to totalize the value of all the tickets issued. In the drawings, I have shown means to add fares of three digits 001 to 9.99, but it will be understood that the scope of the cash counter may be enlarged by providing more counting wheels and actuating mechanism.

Extending through the upper portion of the machine, and having bearings in plates 2 and 3, is a shaft 50 upon which is mounted a unit type wheel 51, a tens type wheel 52 and a hundreds type wheel 53. There is also upon this shaft a thousands and a tens of thousands type wheels 54 which are actuated from the hundreds wheel 53 by a one tooth transfer wheel or any other well-known means. The type wheels 51, 52 and 53 are actuated from the main actuating shaft 57. Each of the type wheels 51, 52 and 53 are provided with a ten tooth pinion 55 which meshes with a thirty tooth gear 56 on the main actuating shaft 57. Attached to the gear 56 is a thirty tooth ratchet 58, the teeth of which are engaged by a pawl 59 on the arm 60. The arm 60 is rigidly secured to the main actuating shaft 57. The pawl 59 has a pin 61 extending therefrom and engaging a setting cam 62 which is also pivoted on the shaft 57. The cam 62 is provided with a segment gear 63 which meshes with a ten tooth rack 64 which slides in guides 65^a on the rear plate 5. The racks 64 are connected to the levers 65 by links 66. The levers 65 are pivoted on the shaft 39 and have projections 67 which engage pins 68 on the cams 69, 70 and 71. There is one of these cams for each of the digits of the cash indications on the type wheel and drum, and as before stated, my invention is not limited to that number. As will be seen from the drawings, the trains of mecha-

85

125

130

nism above described, are in triplicate, one for each digit, and lie between the type wheels 51, 52 and 53, and the cams 69, 70 and 71.

5 In Fig. 7, the adding values of the pins 68 are shown by primed numbers. On each of the cams there is a pin for each of the stations and fare indications, and when a certain fare station and fare is set in printing 10 alinement on the type wheel, their respective pins 68 will engage the projection 67 on the lever 65. The weight of the lever 65, the link 66 and the rack 64 is sufficient to hold the projection 67 in engagement with the 15 pins, but a spring may be provided to assist in this function.

Referring to Fig. 2, it will be seen that when the projection 67 engages one of the pins 68, the rack 64 will be set to a position 20 equal to the value of that pin. If the projection engages pin 5', the rack will be lowered a distance equal to five teeth from the position shown in Fig. 4. Consequently, the segment gear 63 will be rocked a distance 25 equal to five teeth of the ratchet, as the ratchet and gears have the same pitch. If the cam 62 is rocked a distance of five teeth and the shaft 57 and the arm 60 are then rocked, the pawl 59 will advance the 30 ratchet five teeth when the pin 61 will engage the cam surface 62^a and disengage the pawl 59 from the ratchet 58. The same would be the case with any of the pins shown on the cam in Fig. 7. Attached to the 35 ratchet 58 is the gear 56 having the same number of teeth (thirty) as said ratchet 58. This gear 56 meshes with a pinion 55 attached to the type wheels 51, 52 and 53. It will be seen that when the ratchet 58 is 40 moved five teeth on any other number, the same amount of movement will be transmitted to the type wheels. Consequently, if the projection engages one of the pins 68 and the shaft 57 is then rocked, the value of 45 the pin 68 will be set in printing position on its respective type wheel.

Referring to Fig. 14, the angular movement of the lever 60 to rotate the ratchet 58 is indicated by the lines *a a* and *b b*. This 50 lever has an additional movement *b b c c* to actuate the transfer mechanism.

When the type wheels 51 and 52 make one complete revolution, the value of this revolution (ten for the unit wheel and one hundred for the tens wheel) is recorded on the next wheel; this is done after the value of the pins 68 is registered on the type wheels.

Mounted on the shaft 50 are pivoted arms 72. These arms are held in normal position 60 against the rod 73 by springs 74. Extending through each of these arms is a pin 78, and on one end of said pin is a plate 75, which is provided with two notches 76, in either one of which the spring 77 rests to 65 hold the plate 75 in either its upper or lower

position. On the other end of the pin 78 is a pawl 82 which is adapted to engage and actuate the ratchets 79 on the side of the tens and hundreds wheels when the plate 75 is thrown to its lower position and shaft 57 70 actuated. The plate 75 is provided with a projection 80 which is engaged by one of the three pins 81 on the units and tens ratchets 58. As before stated, there are ten teeth on the pinion 55 and thirty teeth on the gear 56. Consequently, upon one revolution of either the unit or tens type wheel, one of the pins 81 will engage the projection 80 and throw the plate 75 to its lower position, thereby throwing the pawl 82 in operative relation with the ratchet 79 of the tens and hundreds wheels. This pawl 82 is thrown while the ratchet is rotating, the pawl riding over the periphery of the ratchet until it comes to rest.

Referring to Fig. 14, it will be seen that the angular movement of the arm 60 is in two parts, represented by the lines *a a b b c c*. The first part of the movement has been referred to, and during the latter part 90 of this movement, the transfer mechanism is actuated. 83 is a projection from the arms 60 which engages a projection 84 on the arms 72 and rocks said arms during the latter part of the movement of the arms 60. If the pawl 82 of either the tens or hundreds ratchet is thrown by one of the pins 81, on the units or tens wheel and the arms 60 and 72 are then rocked, the complete rotation of the unit wheel will be registered on the 100 tens wheel or the complete rotation of the tens wheel will be registered on the hundreds wheel as the case may be. At the end of the forward movement of the arms 72, when the plate 75 is in its lower position or 105 set position, the cam end 85 of the plate 75 engages the inclined surface of the bar 86 thereby throwing the pawl 82 out of engagement with the ratchet 79. The cam end 85 engages the inclined surface of the bar 86 before the pawl 82 has moved the ratchet 79 one tenth of a revolution, but the pawl 82 will stay in engagement with said ratchet a sufficient length of time to move the ratchet one tenth of a revolution. The type wheels 110 51, 52 and 53 are held in printing alinement by the spring-supported rollers 57^a engaging the space between the teeth of the pinions 55. The rollers 57^a are mounted by means of springs on the cross bar 86. The 115 shaft 57 as before stated, is the main operating shaft of the machine and on its right end is provided a crank 87. The extent of the rocking movement of this shaft is shown by the lines *a a* and *c c* of Fig. 14.

Visible ticket indicator and total ticket printing counter.—Mounted in the upper portion of the machine between the frames 1 and 2, is a counter C consisting of wheels 87. These wheels are mounted on a shaft 130

88 which is provided with a knob 89 on the outside of the machine, and by means of which said counting wheels 87 may be set to zero in a well-known manner. These 5 counting wheels 87 are provided with ratchets 90 which are engaged by pawls 91 mounted on the frame 92. The actuating means for the counting wheels 87 are of a well-known type in which the pawls adapted to 10 engage the tens and hundreds ratchet wheels, are held out of engagement with their respective ratchets, by the unit pawl, and are allowed to engage their ratchets by the unit and tens pawl dropping in notches in their 15 ratchets as shown in Fig. 6. The frame 92 is pivoted on the shaft 88 and is rocked from the main actuating shaft 57. The right side plate of the frame 92 straddles the main actuating shaft 57 as at 93, and is provided 20 with a pin 94 which is engaged alternately by the edges 95 and 96 of the disk 97 to rock said frame 92. The wheels 87 are provided with type characters 98 which are in printing alinement with the type wheels 51, 52 and 53. The outer casing of the machine is 25 provided with a sight opening 99 through which the indications on the wheels 87 are visible—see Fig. 13.

The printing counters A and B are actuated from the frame 92—see Fig. 6. As before stated, the unit actuating wheels are rigidly attached to the shaft 39. At the left end of the shaft 39 is a ten tooth ratchet 100 which is engaged by a pawl 101 on an arm 35 102. The arm 102 is connected to the frame 92 by the link 103. It will be seen that upon each movement of the shaft 57, the frame 92 will be rocked and the counters A, B and C will be actuated.

40 *Printing mechanism.*—Mounted in the bottom of the machine and sliding in guides 104 is a plate 105 from which extends upwardly plates 7, 8 and 9. This frame-work supports the printing mechanism. Mounted 45 below the type wheels on the shaft 10 is a platen 106 which is pivoted at 107 to the plates 7 and 9. This platen is actuated by cams 108 on the shaft 109. In the rear of the printing mechanism are mounted two rolls 50 of paper 110 and 111. The roll 110 provides the tickets to be issued, and the roll 111 provides the strip for the printed record. The strips of paper from these rolls pass over the platen 106 and then through feed rollers.

55 Referring to Figs. 8 and 9, it will be seen that on each issuance of a ticket, the ticket strip is fed a greater length than the record strip. To accomplish this, I use differential feeding means having a larger size feed 60 roller for the ticket than for the record. The feed rollers are mounted on shaft 112 which is journaled in the frames 7, 8 and 9. 113 are the larger feed rollers over which the tickets pass, and 114 are the smaller rollers 65 over which the record strip passes. The feed

rollers 113 and 114 are provided with serrated edges 115 which make the feeding of the paper more positive. The strips are kept in contact with their feed rollers 116 on shaft 117. This shaft 117 also has bearings 70 in the frames 7, 8 and 9 and is controlled by springs in pockets 118. To separate the feed rollers from the contact rollers, when placing the paper strips in position, I provide cams 119 pivoted on the shaft 112 and engaging the shaft 117. The feed rollers 113 and 114 and the shaft 112 make a complete revolution upon the issuance of each ticket. The shaft 112 is driven from the shaft 109 which also makes a complete revolution by means 75 of gears 120 on each end of the shaft 112 meshing with the segment gears 121 on the shaft 109. The segment gears 121 are twice the diameter of the gears 120, and as will be seen from the drawings, the feed rollers are 80 rotated during the latter half of the revolution of the cam shaft 109. During the first half of the revolution of the shaft 109, the type wheels are inked and the ticket and record are printed. The type wheels are 85 inked by a felt-inking roller 122 mounted at the lower ends of spring-controlled arms 123. These arms 123 are pivoted to the frames 1 and 4 at 124. The lower ends of the arms 123 have projections 125 which are in the 90 path of the pins 126 on the segment gears 121. At the beginning of the movement of the shaft 109, the pins 126 engage the projections 125 and carry the inking roller 122 under the type wheels a sufficient distance 95 to ink the same. The pins 126 then release the projections 125 which allow the inking roller to spring back to its normal position and out of the way of the platen which next ascends. The shaft 109 is the main actuating 100 shaft of the printing mechanism and is driven during the latter half of the return movement of the main operating lever 87. On the right end of the shaft 109 is a pinion 127 which meshes with a gear 128 pivoted 105 at 129 to the side frame 4; these gears have a three to one ratio. Attached to the gear 128 is a three tooth ratchet 130, said teeth being engaged by the spring-controlled pawl 131 on arm 132. The arm 132 is connected 110 to the arm 132^a on the main actuating shaft 57 by a link 133. During the forward movement of the shaft 57, the pawl 131 descends and engages the lower tooth of the ratchet 130, and during the return movement of said 115 shaft 57, the pawl 131 rotates the ratchet 130 thereby inking the type wheels, printing the ticket, and record, and feeding said ticket and record. The ticket is issued 120 through a slot 134 in the front casing where it may be torn off. The record is fed into the bottom of the machine and is inaccessible to unauthorized persons. The front of the 125 casing is provided with a door 135 hinged at 136. The printing mechanism is slidingly 130

mounted and may be removed through the door 135 for the purpose of renewing the paper.

In addition to the type wheels mounted on shaft 10 to print the record and ticket, I also provide identification keys 137 which are removably mounted in the side frames 1 and 4. These identification keys are the same as in some of my prior patents. I 10 also provide type 138 which are mounted on the frames 2 and 3. These type print the number of the machine and may be used on the record to identify the station with the ticket. The record is only accessible to the 15 inspector who is provided with a key to the lock 139 of the door 135. After removing the printed record from the machine, the inspector takes a record from the cash counter and visible indicator at the top 20 of the machine. 140 is a platen pivoted at 141. This platen lies under the type wheels 50, 51 and 52 and the type characters on the wheels. The platen 140 is pressed against the type by the cams 142 on the 25 shaft 143. The shaft 143 is provided with a knob 144 on the outside of the machine. When the inspector wishes to secure a record of the cash counter and visible indicator, the end of the record strip is inserted in the 30 slot 145 in the casing which brings the record strip under the type. The knob 144 is then rotated which takes an embossed impression.

Referring to sheet 7, in Figs. 8 and 9, I 35 have shown the ticket and record as issued from a machine provided with a consecutive printing counter as described. In Figs. 10 and 11, the tickets shown are issued from a machine not provided with consecutive 40 printing counters, but in lieu thereof, the tickets themselves are serially numbered. Each machine has substantially a universal capacity in that it may be utilized in the service of any railway company or transportation line, or at any station of any railway company without altering or changing any of the mechanical features in the machine, common to them all. In adapting 45 the machines for service on any particular 50 railway, it is only necessary to arrange the type on the peripheries of the printing wheels to print the names of the stations and prices of the tickets. The identification devices, the dating devices, the consecutive 55 numbering devices, the register number devices, the devices for printing the value of each ticket, the devices for specializing the tickets, such for example, as half fare tickets, clergyman tickets etc., the devices for printing 60 the total number of tickets sold, and the devices for printing the total value of all the tickets sold, are features which are common to all of the machines.

The tickets as shown in Fig. 10 are provided with the numbers thereon before the

roll is placed in the machine. The tickets shown in Fig. 8 have the serial numbers printed thereon in the machine.

Figs. 1 and 1^a, show identification devices 137, one to print the identification of the 70 ticket seller on the ticket, and the other to print it on the duplicate record. In some cases it may not be desirable to print the ticket seller's identification on the tickets, but to print it only upon the record; in 75 this case, one of the identification printing devices 137 may be omitted from the machine.

The month wheel and the date wheel may be used upon the record for a double purpose, see Figs. 10, 11 and 15, for example, after indicating and printing the date on the record of the first ticket, the month and day wheels 12 and 19 may be further used for printing the time by hours, the date 85 wheel from 1 to 5, for printing the fractions of hours, for example, "1" to signify 10 mins.; "2" to signify 20 mins.; 3 to signify 30 mins.; etc. For even hours, the star is used in place of any of the figures used 90 to indicate a fraction of an hour.

To further illustrate: In starting in the morning, the machine will begin operation at "1"; the record will show this to be 1 o'clock a. m.; the second "1" to be 1 95 o'clock p. m. In such case, a double set of indicators may be used, disconnected, to be operated separately, as shown in Fig. 15, one on each side of the machine; one to indicate and print the dates on the tickets, and 100 the other the hours and minutes on the record as above described in addition to the dates. In this case the shafts 17 and 24 are omitted as shown in Fig. 15. 28' designates the day indicating wheel, 29' the 105 month indicating wheel, 31' and 32' are the respective shafts of said wheels, 34' and 35' 110 designate the gears on said shafts which mesh with gears 20 and 13 on the day and month type wheels 18 and 11 which have been referred to. 50^b is an indicator under 115 which revolves the day and month wheels 28' and 29'.

The operation of my machine is as follows: When it is desired to issue a ticket, the 115 drums 28, 29 and 30 are rotated to bring the selected month, date and class of ticket under the indicator 50^b. This operation brings the selected type in printing alignment with the platen. The station printing drum is 120 then rotated until the desired destination coincides with the indicator 50^a. By means of the figures denoting the ticket values or prices opposite the stations on said drum, the operator will know in advance the cost 125 of such ticket. This last operation brings the station type in printing alignment with the platen. By this operation, the cams 62 are also set by the racks 64, links 66, levers 65, projections 67, and the pins 68 on cams 130.

69, 70 and 71. The machine is now set and the ticket is next printed and issued. The operator next rocks the main operating shaft 57 through means of the lever 87. 5 During the forward movement of the lever, the total cash counter and the counters A, B and C are actuated, and during the reverse movement, the type wheels are inked, the ticket and record are printed and the 10 ticket is issued, which completes the operation.

I claim:

1. In a machine of the type specified, printing devices arranged in duplicate upon 15 a common axis, one of said printing devices being adapted to print tickets and the other to print a record of said tickets, a platen between which and said printing devices the ticket strip and record strip pass, means 20 mounted on a common actuator and in direct operative relation with the paper strips for imparting different feed movements to the ticket strip and the record strip, and means for supporting rolls of paper from 25 which said paper strips are fed.

2. In a machine of the type specified, a series of printing devices arranged in duplicate upon a common axis, one of said printing devices being adapted to print a ticket 30 and the other to print a record of said ticket, a platen between which and said printing devices the ticket strip and record strip pass, and means for imparting different feed movements to the ticket strip and the record 35 strip, said means consisting of a shaft, variable feed rollers mounted thereon, the roller for the ticket strip being larger in diameter than the roller for the record strip, and means for maintaining the ticket and 40 record strips in contact with said rollers.

3. In combination with printing devices arranged in duplicate upon a common axis, one of said printing devices being adapted 45 to print the price on a ticket and the other to print a record of said ticket, means mounted on a common shaft in direct operative relation with the paper strips for imparting different feed movements to the ticket and record strips, and means adapted 50 to support rolls of paper from which said paper strips are fed.

4. In a ticket issuing and auditing machine, a series of printing devices arranged in duplicate, one of said devices being

adapted to print on a ticket strip, and the other on a record strip, and means mounted on a common shaft and in direct operative relation with the paper strip for imparting different feed movements to the ticket strip and the record strip. 60

5. In a ticket issuing and auditing machine, a series of printing devices arranged in duplicate, one of said printing devices being adapted to print a ticket and the other to print a record of said ticket, a platen between which and said printing devices the ticket strip and the record strip pass, and means for imparting different feed movements to the ticket strip and the record strip, said means consisting of a shaft, variable 70 feed rollers mounted thereon, the roller for the ticket strip being larger in diameter than the roller for the record strip, and means for maintaining the ticket and record strips in contact with said rollers. 75

6. In a ticket issuing and auditing machine, a series of printing devices arranged in duplicate, one of said printing devices being adapted to print a ticket and the other to print a record of said ticket, a platen between which and said printing devices the ticket strip and record strip pass, and means for imparting different feed movements to the ticket strip and the record strip, variable feed rollers for differentiating the feed for 85 the ticket strip and the record strip, and means for maintaining the ticket and record strips in contact with said rollers. 80

7. In a combination with printing devices arranged in duplicate, one of said printing devices being adapted to print a ticket and the other to print a record of said ticket, differential means mounted on a common shaft and in direct operative relation with the paper strips for imparting different feed 90 movements to the ticket strip and the record strip, means for maintaining the ticket and record strips in contact with said feeding means, and means adapted to support rolls of paper from which said paper strips are 100 fed. 95

In testimony whereof I affix my signature, in presence of two witnesses.

JOHN F. OHMER.
